[57] CLAIM

The ornamental design for a portfolio for an attache case or the like, as shown and described.

DESCRIPTION

FIG. 1 is a perspective view of a portfolio for an attache case or the like, showing our new design.

FIG. 2 is a front elevational view thereof.

FIG. 3 is a rear elevational view thereof.

FIG. 4 is a right side elevational view, the left side elevational view being a mirror image thereof.

FIG. 5 is a top plan view thereof;

FIG. 6 is a bottom plan view thereof; and

FIG. 7 is a perspective view thereof in the closed condition, the environmental structure shown in dashed lines being for illustrative purposes only.

The stippling in the drawing is to illustrate surface contrast and not color.
